UNITED STATES PATENT OFFICE.

FRED BECKER, OF CLEVELAND, OHIO.

DESIGN FOR MACARONI OR OTHER EDIBLE PASTE PRODUCT.

43,813.

Specification for Design.

Patented Apr. 8, 1913.

Application filed January 10, 1913. Serial No. 741,334. Term of patent 14 years.

To all whom it may concern:

Be it known that I, FRED BECKER, a citizen of the United States, residing at Cleveland, in the county of Cuyahoga and State of Ohio, have invented a new, original, and ornamental Design for Macaroni or other Edible Paste Product, of which the following is a specification, reference being had to the accompanying drawing, forming part thereof, in which—an elevation; Figs. 3 and 4 edge views projected from Fig. 2, and Fig. 5 is a bottom view, of my macaroni or other edible paste product.

I claim:

The ornamental design for macaroni or other edible paste product.

FRED BECKER.

Witnesses:

CHAS. F. DAUENHAUER,

R. J. SMITH.
